US00D764047S

(12) **United States Design Patent**
Bjelovuk et al.

(10) **Patent No.:** **US D764,047 S**
(45) **Date of Patent:** **** Aug. 16, 2016**

(54) **THERAPY UNIT ASSEMBLY**

(71) Applicant: **Smith & Nephew, Inc.**, Memphis, TN
(US)

(72) Inventors: **Brian P. Bjelovuk**, Westerville, OH
(US); **Carrie Lee Childress**, Dallas, TX
(US); **Kealoha Young Deutsch**, Odessa,
FL (US); **William W. Gregory**,
Gainesville, FL (US); **Kathryn Ann
Leigh**, Saint Petersburg, FL (US);
Andrew P. Muser, Saint Pete Beach, FL
(US); **Felix C. Quintanar**, Hull (GB);
Billy J. Ratliff, Commerce Township,
MI (US); **Michael T. Roller**, Covington,
KY (US); **Robert H. Roth**, Cincinnati,
OH (US); **Mark Schaefer**, Largo, FL
(US)

(73) Assignee: **Smith & Nephew, Inc.**, Memphis, TN
(US)

(**) Term: **14 Years**

(21) Appl. No.: **29/492,116**

(22) Filed: **May 28, 2014**

(51) LOC (10) Cl. **24-01**

(52) U.S. Cl.

USPC **D24/108**

(57) **CLAIM**

The ornamental design for a therapy unit assembly, as shown
and described.

DESCRIPTION

FIG. 1 is a top, front, and left side perspective view of a
therapy unit assembly.

FIG. 2 is a bottom, rear, and right side perspective view
thereof.

FIG. 3 is a top plan view thereof.

FIG. 4 is a bottom plan view thereof.

FIG. 5 is a left side view thereof.

FIG. 6 is a right side view thereof.

FIG. 7 is a front view thereof; and,

FIG. 8 is a rear view thereof.

The broken lines in the drawings illustrate portions of the
therapy unit assembly which form no part of the claimed
design.

1 Claim, 6 Drawing Sheets
